UNITED STATES PATENT OFFICE.

MAUDE BLANDIN, OF PEORIA, ILLINOIS.

DESIGN FOR AN AUTOMOBILE DIRECTION-SIGNAL CASING.

Application filed November 10, 1924. Serial No. 11,837. Term of patent 7 years.

To all whom it may concern:

Be it known that I, MAUDE BLANDIN, a citizen of the United States, residing at Peoria, in the county of Peoria and State of Illinois, have invented a new, original, and ornamental Design for an Automobile Direction-Signal Casing, of which the following is a specification, reference being had to the accompanying drawing, forming part hereof.

Figure 1 shows my design in perspective as the signal casing is viewed from the front.

Figure 2 shows my design in perspective as the signal casing is viewed from the rear.

I claim:

The ornamental design for an automobile direction signal casing as shown.

In testimony whereof I affix my signature.

MAUDE BLANDIN.
